Design No. 2,816, dated October 22, 1867.

DESIGN FOR A BOTTLE.

The Schedule referred to in these Letters Patent and making part of the same.

TO ALL WHOM IT MAY CONCERN:

Be it known that we, HENRY SCHLICHTER and H. A. The base A of the bottle consists of a simple disk supporting the body B, which is made in the form of an ear of corn partly enveloped in the husk, and which is surmounted with the neck and mouth D.

We claim the design for a bottle, substantially as represented in and by the accompanying drawing.

In testimony whereof we have signed our names to this specification in the presence of two subscribing witnesses.
